UNITED STATES PATENT OFFICE

JAMES G. PRAGER, OF WORCESTER, MASSACHUSETTS, ASSIGNOR TO PRAGER CO., INC.,
A CORPORATION OF NEW YORK

DESIGN FOR WALL PAPER OR SIMILAR MATERIAL

Application filed March 17, 1930. Serial No. 34,942. Term of patent 3½ years.

To all whom it may concern:

Be it known that I, JAMES G. PRAGER, a citizen of the United States, and resident of Worcester, in the county of Worcester and State of Massachusetts, have invented a new, original, and ornamental Design for Wall Paper or Similar Material, of which the following is a specification.

In the accompanying drawing:—

The figure is a surface view of a piece of wall paper or similar material showing my new design. The area within the dot and dash lines represents one complete unit of the design, and that outside of the dot and dash lines represents repeat units arranged around the complete unit as illustrated.

I claim:—

The ornamental design for wall paper or similar material as shown and described.

Signed at New York, in the county of New York and State of New York, this 14th day of March, A. D. 1930.

JAMES G. PRAGER.
